UNITED STATES PATENT OFFICE.

GEORGE B. RATTERMANN AND WALTER W. GARRISON, OF BIRMINGHAM, ALABAMA.

AUTOMATIC FIRE-ALARM.

1,195,499.

Specification of Letters Patent. Patented Aug. 22, 1916.

Application filed April 21, 1915. Serial No. 22,929.

To all whom it may concern:

Be it known that we, GEORGE B. RATTERMANN and WALTER W. GARRISON, citizens of the United States, residing at Birmingham, 5 in the county of Jefferson and State of Alabama have invented a new and useful Automatic Fire-Alarm, of which the following is a specification.

This invention has reference to automatic 10 fire alarms, and its object is to provide an alarm mechanism and system designed particularly for installation in buildings and for use in conjunction with municipal fire alarm systems.

15 In accordance with the present invention a building is equipped with as many local alarm sending apparatus as may be needed with each such apparatus under the control of one or more devices responsive to fire 20 conditions, so that in the event of a fire and before such fire has gained uncontrollable headway the alarm sending apparatus is set into operation to transmit to the proper authorities such signals as may indicate the 25 location of the fire, and, if desired, simultaneous with the transmission of such signals an audible or telephonic message is sent to a telephone central station for separate transmission to the proper authorities by 30 the telephone central station operator.

The present invention comprises mechanism whereby these operations are brought about in the event of a fire, and also includes means whereby the municipal system is 35 maintained intact in working condition after the sending of such an alarm even though the signal sending apparatus should fail to stop at the proper position as might sometimes happen. For this purpose the present 40 invention, which causes electrical transmission of the signals, contemplates the use of a switch which will cause the closing of the circuit of the street fire alarm system even though the local transmitting mechanism 45 fails to stop at the proper point, so that the street system remains in commission.

Since it is often desirable to turn in an alarm before conditions reach the point causing the automatic sending of the alarm, the 50 present invention contemplates the association with the automatic alarm of a manually operable circuit-closing means which may be of the character requiring the breaking of a sheet of glass in order to turn in the alarm, or such manually operable circuit closer may be of some other type where-

by the automatic alarm sending devices are set into motion.

The invention will be best understood from a consideration of the following detailed description, taken in connection with the accompanying drawings, forming part of this specification, with the further understanding that while the drawings show a practical form of the invention, the latter is 60 not confined to any strict conformity with the showing of the drawings, but may be changed and modified so long as such changes and modifications mark no material departure from the salient features of 65 the invention.

In the drawings:—Figure 1 is a plan view of the signal sending apparatus. Fig. 2 is an elevation of the signal sending apparatus as seen on the side remote from the telephone. Fig. 3 is a section on the line 3—3 of Fig. 1. Fig. 4 is a section on the line 4—4 of Fig. 1. Fig. 5 is an elevation of the structure of Fig. 1 as viewed from the left hand end thereof. Fig. 6 is a section on the line 6—6 of Fig. 1 with distant parts omitted. Fig. 7 is a section on the line 7—7 of Fig. 1. Fig. 8 is a section on the line 8—8 of Fig. 1. Fig. 9 is a section on the line 9—9 of Fig. 1, distant parts being 80 omitted. Fig. 10 is a diagram of the local fire alarm system. Fig. 11 is a perspective view of the normally operable circuit closer. Fig. 12 is a perspective view of a portion of the interior mechanism of the device of 85 Fig. 11.

Before describing the system and the manner in which it operates the mechanical and electromechanical structures and devices employed will be described.

95 Referring first to Figs. 1 to 9 and associated figures, there is shown a base 1 upon which at a point about midway of its length there is mounted a spring motor. This motor has side plates 2, 3 connected by spacing 100 posts 4 where needed. Journaled in the side plates 2, 3 is a winding arbor 5 extending centrally through a spring drum 6 such as is employed in spring motors or clock trains, or the like, and this drum is assumed to contain a suitable spring, which latter being of the ordinary construction is not shown in the drawings.

105 The spring drum 6 has attached to it a large gear wheel 7 in mesh with a pinion 8 on an arbor 9 journaled in the plates 2 and 3, and the pinion 8 is in mesh with a gear

wheel 10 fast to a drum 11 mounted on an arbor 12 journaled in the plates 2 and 3.

The arbor 9 carries a gear wheel 13 meshing with a pinion 14 on another arbor 15 5 journaled in the plates 2 and 3. Mounted on the arbor 15 is a gear wheel 16 meshing with a pinion 17 on a shaft 18 also journaled in the plates 2 and 3 and extending through the plate 3 where it carries a gear wheel 19 10 and a pulley 20 both fast to the arbor 18. Also journaled in the plates 2 and 3 near one edge thereof is a shaft 21 carrying a pulley 22 connected to the pulley 20 by a belt 23, so that the pulley 20 to which motion is imparted in a manner to be described transmits motion to the shaft 21 by way of the belt 23 and pulley 22. The shaft 21 projects beyond the plate 2 and there carries a mandrel 24 of a size and shape to receive 15 a sound record tablet 25, which tablet is shown in the drawings as of the cylindrical form, but it will, of course, be understood that by an appropriate change in the mechanism a disk tablet may be employed, the interchangeability of sound reproducing mechanisms being well understood.

The gear wheel 13 is in mesh with a pinion 26 on a shaft 27 journaled in the plates 2 and 3 and extending beyond both plates to 30 the ends of the base plate 1 where the shaft is suitably mounted in end plates or uprights 28, 29 erected on the base plate 1.

The shaft 27 between the plate 2 and upright 28 has a screw threaded portion 30 and 35 between the plate 3 and upright 29 has a screw threaded portion 31. In the particular construction shown the threaded portions 30 and 31 are oppositely threaded one to the other.

40 Connecting the upper end of the upright 28 to the plate 2 is a rod 32 located on one side of the threaded end 30 of the shaft 27, and on the other side of said shaft is another rod 33 extending between the plate 2 and the upright 28. The shaft end 30 and the two rods 32 and 33 are all shown as on approximately the same level, but this is not an obligatory arrangement, since they may be otherwise located.

50 Mounted on and slidable along the rod 32 is a sleeve 34 fast to one end of an arm 35 extended along the screw threaded end 30 of the shaft 27 and over the rod 33. Immediately over the threaded end 30 of the shaft 27 the arm 35 is provided with a half nut 36; that is, the nut is incomplete circumferentially so as to rest upon and mesh with the threaded portion 30 of the shaft 27. The arm 35 is supported by the rod 33 and 55 at the end of the arm 35 remote from the sleeve 34, which end extends over the mandrel 24, the arm carries a sound reproducing sound box 37, shown in the drawings as of the type customarily employed for the reproduction of the kind of sound records pro-

duced upon cylindrical record tablets. This sound box is taken as typical of any suitable type of sound box, and the arm 35 with the driving and supporting means therefor is to be taken as typical of any sound reproducing apparatus adaptable to the present invention. 70

The sound box 37 is shown as supporting an amplifying horn 38 by means of a neck 39, and this horn is presented toward a 75 mouth piece or receiving intensifier 40 of a telephone transmitter which is assumed to be inclosed in a box 41.

Carried by the plate 3 is an outstanding bracket 42 in the outer end of which is journaled one end of a shaft 43, the other end of said shaft being journaled in the plate 3 adjacent to which the shaft carries a pinion 44 in mesh with the gear wheel 19. Mounted on the shaft 43 adjacent to the plate 3 80 85 is a disk 45, which, as will hereinafter appear, constitutes a friction disk. This disk is not fixed to, but may slide upon the shaft 43, and is connected to the similar ends of spring strips 46, which at the other ends are 90 all made fast to a collar 47 on the shaft 43, said collar being held in any suitable adjusted position by a set screw 48. Balls or weights 49 are made fast to each spring strip 46. The disk 45, springs 46, collar 47, 95 weights 49 and shaft 43 represent a familiar form of centrifugal governor frequently employed in connection with spring or other motors, and may be taken as typical of any suitable form of governor adapted to the 100 purposes of the present invention.

Mounted on the plate 3 are closely associated but spaced ears 50, constituting journals for a trunnion pin 51 carried by a lever 52, although, of course, the lever might be 105 made to turn upon the pin 51, since the purpose of the trunnion pin 51 is to serve as a pivot or fulcrum. The lever 52 has one arm extended until opposite that face of the disk 45 remote from the plate 3, and there the 110 arm carries an adjustable engaging member 53 adapted to bear upon the disk 45. In the drawings the bearing member is shown as an ordinary screw, but it will be understood that any bearing member such as is 115 employed in connection with centrifugal governors of the type shown in the drawings may be used.

At the other end the lever 52, which lever in the showing of the drawings is an upright lever, is expanded into an armature 54 in operative relation to the polar ends 55 of an electromagnet 56 carried by the plate 2 and extended into suitable operative relation to the armature end 54 of the lever 52. 120 Fast at one end to the plate 3 is a spring 57 bearing at the other end against the lever 52 on the side of the pivot 51 remote from the screw 53 and imparting to the lever a constant tendency to bear against the disk 45. 125 130

The train of gearing under control of the spring in the spring drum 6 is normally held against motion by the frictional engagement of the screw 53 with the disk 45. 5 When the magnet 56 is energized the armature 54 is attracted against the action of the spring 57, thereby moving the screw 53, which operates as a brake member, from braking pressure upon the disk 45 and the 10 train of gearing is released. The rotation of the governor as it speeds up moves the disk 45 again into engagement with the screw or brake member 53 with sufficient force to limit the speed of rotation. The 15 movement of the train of gearing continues so long as the magnet 56 is energized, but when the circuit through the magnet is broken the spring 57 returns the lever 52 to its first position and the pressure of the 20 brake member 53 upon the disk 45 is sufficient to hold the governor against rotation, and thereby hold the entire train of gearing against further rotation.

Secured to the plates 2 and 3 and extending between them is a block 58 of insulating material located adjacent to the drum 11. Carried by the block 58 are spring fingers 59 having free ends 60 tending toward the drum 11. Mounted on the block 58 are 30 other fingers 61 in the path of the ends 60 of the fingers 59, but the tendency of the fingers 59 is to move away from the fingers 61 for a short distance.

The drum 11 carries pins 62, 63 projecting generally radially therefrom and so disposed with relation to the ends 60 of the fingers 59 that on the rotation of the drum 11 the pins 62, 63 engage the ends 60 of the fingers 59 and move them into contact with 40 the fingers 61. The pin or engaging member 62 has a prolongation 64 extended in substantially concentric relation to the axis of rotation of the drum 11 and the outer surface of this extension 64 is roughened or 45 serrated, as shown at 65, so that on moving into engagement with the end 60 of the respective finger 59 in its path, the finger 59 is moved into and out of engagement with the finger 61 a number of times in rapid 50 succession. The pins 63 may be ordinary projecting pins in the path of which are other fingers 59.

In the ordinary operation of the system the pin 62 may be considered as a hundreds 55 pin, while the pins 63 may represent tens and units, and if there be a greater number of series of pins they may represent higher denominations.

It is customary to indicate fire alarm stations numerically, and hence the pins or a 60 succession of pins in the same circumferential row represent certain numbers. For instance, if in the units row there be one pin, the signal transmitted represents 1. If in 65 the tens row there be three pins the number

of impulses transmitted is 3 and if in the hundreds row there be seven pins, the number of impulses transmitted is 7, wherefore the number of the station under the conditions assumed would be 731. If the number of the station be less than one hundred, the pins 62 and 63 are arranged accordingly to represent tens by the pin 62 and units by a row of pins 63. 70

If it be assumed that a signal is being 75 sent the first sound heard at the receiving station is a very rapid succession of noises due to the rapid making and breaking of the circuit by the elongated portion 64 of the pin 62, and when this pin leaves the respective finger 59 a distant signal sound is produced to be followed by other signal sounds, usually the stroke of a bell if the number of the station in tens or hundreds, as the case may be, is above 1. Following the 80 first number transmitted will be a second number, and often a third number, depending upon the number assigned to the particular station.

The fingers 59 and 61 have respective conductors 66 and 67 connected thereto, and these conductors may be continued to some central point where fire signals are received, and there may be located any suitable receiving apparatus, the construction of which 95 need not be entered into here.

During the sending of the signal in the manner described, motion is imparted to the shaft 27 and the threaded portion 30 thereof imparts to the sound reproducer 37 a progressive movement over the tablet 35, the latter being rotated in the manner already described. The record upon the tablet 25 may be of any suitable character, and the sounds are uttered by the amplifier 38 into 100 the receiving mouth piece 40 of the telephone transmitter. By means to be described the transmitter is automatically coupled up into circuit to the telephone central station where the operator receives the information 105 conveyed by the sound record. Such information may give to the central station operator the location of the fire, and even the specific portion of the building where the fire is in progress. This information is at once 110 conveyed to fire headquarters, so that should the first signal fail to reach headquarters the 115 telephone information may reach headquarters.

Connecting the top of the upright 29 with 120 the end plate 3 in spaced relation one to the other and on opposite sides of the threaded end 31 of the shaft 27 are rods 68, 69, respectively.

Carried by the upper end of the upright 125 29 is an elongated block 70 of insulating material. Mounted on this block is a switch lever 71 carried at one end by a pivot 72 which may be in the form of a screw or bolt extending through the block 70 and sur- 130

rounded by a spring 73 conveniently seated in a countersink 74 formed in the block 70, one end of the spring being made fast to the block and the other end engaging the 5 switch lever 71. The spring 73 imparts to the switch lever 71 a constant tendency to move in one direction. The switch lever 71 is held in one position in opposition to the normal tendency of the spring 73 by a latch 10 lever 74 mounted between ears 75 fast to the top of the block 70. The lever 74 has one end 76 in the form of a tooth adapted to engage over one edge of the lever 71 to hold the latter against movement under the action 15 of the spring 73. The other end of the lever terminates in a downturned nose 77 spaced from that edge of the block 70 toward the plate 3. A spring 78 tends to maintain the lever 74 in such position that the tooth 76 20 will snap into the path of the lever 71 when the latter is moved to a position permitting such action of the tooth 76. An appropriate force applied to the nose 77 in position to act thereon to one side of the pivot of the 25 lever 74 will rock the lever against the action of the spring 78 so as to lift the tooth 76 out of the path of the lever 71, and the latter will then move on the pivot 72 under the action of the spring 73.

30 At one side of the block 70 in the path of the switch lever 71 remote from the pivot 72 are two contact terminals 79, 80, respectively, these contact terminals being bridged by the lever 71 when the lever is locked 35 by the engagement of the tooth 76 therewith. On the opposite side of the block 70 are other contact terminals 81, 82, respectively, engaged and bridged by the lever 71 when released from the latch tooth 76 and moved 40 into engagement with the terminals 81, 82, under the action of the spring 73. The lever 71 is provided with a handle 83 whereby the lever may be moved from engagement with the contacts 81 and 82 into engagement 45 with the contacts 79 and 80 where the lever is held by the latch tooth 76.

The contact 79 is connected by a conductor 84 to one side of the magnet 56. The contact 80 is connected to a conductor 85 to 50 which reference will hereinafter be made. The other side of the magnet 56 is connected to a conductor 86 to which reference will hereinafter be made.

The circuit terminals 81 and 82 are connected to respective conductors 87, 88 leading to the street for a purpose to be herein-after described.

Mounted to slide on the rod 69 is a sleeve 89 carrying two closely associated spaced 60 side plates 90 constituting a carriage. The end of each plate remote from the sleeve 89 is provided with a projecting finger 91 adapted to rest upon and slide along the rod 68. Mounted between the side plates 90 is 65 a rock member 92 supported by a pivot 93

carried by the two plates 90. At one end the rock member 92 is formed with a mutilated or half nut 94 suitably threaded to engage the threads of the threaded portion 31 of the shaft 27, and the arrangement is such 70 that when the half nut portion 94 of the member 92 is in engagement with the threaded portion 31, no ordinary force exerted in the action of the apparatus will lift the member 92 or the carriage 90 in a direction to release the mutilated nut 94 from engagement with the threaded portion 31. A spring 95 carried by the plates 90 and bearing upon the member 92 serves to maintain the nut 94 in engagement with the 80 threaded portion 31. The member 92 is traversed by a pin 96 adapted to engage the side plates 90 close to the fingers 91, these side plates being each provided with a notch 97 for the reception of the respective end of 85 the pin 96. The end of the member 92 remote from the nut portion 94 is formed into a finger piece 98 projecting from between the plates 90 in position to be readily caught by the finger of an operator to rock the 90 member 92 on its pivot 93 against the action of the spring 95 to move the nut portion 94 away from the screw 31, and then the carriage made up of the plates 90 and parts carried thereby may be moved along the rods 95 68 and 69 to any appropriate extent. Carried by that plate 90 toward the block 70 is a projection 99, so located as to strike the nose 77 of the lever 74 at a low point thereon, and when this occurs a further movement 100 of the carriage 90 under the action of the screw 31 causes a rocking of the lever 74 to unlatch the switch lever 71, so that the latter moves from its normal position of bridging relation to the contacts 79 and 80 into bridging relation to the contacts 81 and 82, this being for a purpose to be described.

In Fig. 10 there is diagrammatically represented a fire alarm system in which the structures already described are utilized.

Mains 100, 101 are installed in the building where the fire alarm system is located, and these mains are charged in any suitable manner as by an appropriate source of current represented by a battery 102, although 115 it will be understood that any other source of electric energy may be used. The mains 100 and 101 are carried wherever needed and may be branched in any direction necessary for the proper installation of the system. One of the mains, say, the main 101, has the conductor 85 connected thereto and to the other main there is connected a conductor 103 having its continuity interrupted at an appropriate point by a thermostatic or other suitably responsive device 104. The purpose of the device 104 is to cause a completion of the electrical continuity of the conductor 103 in the event of a fire in the neighborhood of the device 104. There are 120 125 130

numerous devices for the purpose, some causing a closure of the circuit by the action of heat, others causing the closure of the circuit by the release of a normally open circuit device having a constant constraint toward the closed circuit position but held open by some means readily affected by heat.

There are other devices which might be employed which become actively responsive in the event of a fire either close to or in the general neighborhood of the circuit closing device. Any device whatever adapted for the purpose may be considered as represented by the device 104 in the diagram which is conventionally shown as a thermostatic circuit closer.

The conductor 103 also includes a contact 105 and is continued to one side of an electromagnet 106, the other side of which is connected to the conductor 86 leading to the electromagnet 56. Under the control of the magnet 106 is an armature 107 in turn controlling a latch 108 normally holding a contact 109 in the open circuit position, said contact having constant constraint toward the closed circuit position by means of a spring 110 or otherwise. In the path of the contact 109 is another contact 111 in circuit with which is the telephonic transmitter 41.

The contact 109 and the transmitter 41 are respectively connected to leads 112 and 113, which may be considered as carried to a telephone central station, so that in the event of the closure of the circuit at the contacts 109 and 111 a central station operator is notified. By having the notification of a character apprising the central station operator of the fact that the call comes from a fire alarm installation, the operator at once notifies the fire authorities of the message received, such arrangement being a check upon the automatic sending of the alarm directly to the fire headquarters.

Connected to the main 100 is another conductor 114 terminating at the contact 115 close to but separated from the contact 105. Associated with the contacts 105 and 115 is a bridge member 116 carried by a spring arm 117. The contacts 105 and 115 and the bridging member 116 and arm 117 are mounted in a box 118 provided with a glass front 119 similar to the glass protectors of fire alarm boxes and requiring the breaking of the glass in order that the bridge member 116 may be moved into bridging relation to the contacts 105 and 115. Since it is desirable that the bridging member maintain its position after being moved into circuit closing relation to the contacts 105 and 115, the parts may follow the construction of an ordinary jack-knife switch.

Difficulty has been found in attempting the closure of a circuit by breaking the glass protecting plate because of the liability of particles of glass getting on to the contacts

and preventing a proper closure thereof. To avoid this the glass plate 119 has a passage 120 therethrough, which passage may be provided with a bushing 121. Mounted in the bushing 121 is a knob 122 provided with a stem 123 in normally close relation to the bridging member 116. In event of a fire a blow is delivered to the knob 122, which blow results in the shattering of the glass 119, but before any particles of glass can possibly reach the contacts 105 and 115, the bridging member 116 has engaged them in good electrical contact with both.

Each conductor 103 may include as many devices 104 in multiple as may be found expedient. In a large building a fire alarm apparatus such as described with reference to Fig. 1 and associated figures might be installed on each floor with thermostatic or other devices 104 located at many points on each floor, so that a fire starting almost anywhere upon a floor will quickly affect a thermostatic device 104 to cause the operation of the alarm sending mechanism transmitting to the fire headquarters a number alarm and to the central telephone station such information as may be contained upon the sound record provided. Such sound record may contain some expression indicative of the presence of fire, and also state the building location and the fire location, and such other information as may be useful, and the arrangement is such that this information is repeated one or two times as a matter of precaution the same as it is customary to similarly repeat the number alarm to avoid any chance of error which might occur if the alarm number were given but once.

Suppose that with an installation such as represented in Fig. 10 a fire should occur, and some one of the thermostatic devices 104 be affected by the fire so as to close the circuit at the thermostat. The conductors 100 and 101 are assumed to be always charged. Then there is provided a circuit from the battery 102 to the conductor 100, thence by way of the conductor 103 and thermostatic device 104 to the magnet 106 and by way of the conductor 86 to the magnet 56, the circuit continuing through the conductor 84, switch lever 71, and conductor 85 to the main 101 and from thence returning to the battery 102. The energization of the magnet 106 by the circuit thus traced causes a movement of the latch 108 in a direction to release the contact 109, which latter then moves into engagement with the contact 111, and so closes the transmitter circuit to central. The energization of the magnet 56 causes a release of the mechanical actuating devices represented by the train of gearing and parts driven thereby. This results in the rotation of the drum 11 causing repeated consecutive openings of the circuits including the conductors 66 and 67 to thereby

cause the production of the alarm at the fire headquarters in the usual way, except that at the start the serrated portion 65 of the pin 62 produces a preliminary attenuation-direction effect at the fire headquarters immediately preceding the sounding of the alarm. The pins 62 and 63 are, it will be understood, so disposed that the alarm is appropriately sent and repeated as is customary in the sending of fire alarms. While the sending of the impulses producing the alarm at headquarters is proceeding, the carriage 90 is being propelled by the screw 31 toward the block 70 and the sound box 37 is being propelled by the screw 30 along the record 25. Since at the start of the alarm giving operations the telephone transmitter 41 has been connected up to central, the sound uttered by the mouthpiece or amplifier and received by the mouthpiece 40 is heard by the central operator. The movement of the carriage 90 is such that at the termination of the signal sending operations the projection 99 is brought into contact with the latch lever 74 and the switch arm 71 is released, thereby cutting out the magnets 56 and 106 and cutting in the conductors 87 and 88. When the magnets 56 and 106 are deenergized the parts controlled thereby are released, so that the telephone transmitter 41 is cut out of circuit and the motor driving the alarm sending apparatus and other parts is stopped by the braking action of the brake member 53. Should it be desirable to send an alarm when the conditions are not such as to cause an automatic sending of the alarm by the closure of some one of the thermostatic devices 104, the apparatus may be set into operation by delivering a blow upon the knob 122, thereby shattering the glass 119 and causing the bridging member 116 to close the circuit between the contacts 105 and 115, whereupon the circuit is closed as before, except that instead of the circuit being completed through the conductor 103 it is completed through the conductor 114. The operations described as to the working of the apparatus are the same as those which occur when the circuit is closed by a thermostatic device 104.

By properly protecting the alarm sending apparatus and by protecting the main and branch conductors, such parts are not usually damaged by fire, so that when the fire has been subdued the sending apparatus may be reset for subsequent operation.

The spring used to actuate the gear train in the structure shown may be of a character permitting successive operations of the device without rewinding. The carriage or traveler 90 is returned to its first or initial position toward the plate 3 by first moving the member 92 so as to release the nut 94 from the screw 31 and then sliding the trav-

eler away from the block 70 to the desired extent. The sound box 37 is also returned to the beginning of the record 25 and this may be done by simply lifting the sound box so as to release the part nut 36 from the screw 30 and the return of the sound box to engagement with the sound record causes a reengagement of the nut 36 with the screw 30. Finally the switch lever 71 is moved against the action of the spring 73, the knob 83 forming a convenient manipulating means. The movement of the lever 71 is continued until the lever is caught by the latch tooth 76, at which point the lever 71 bridges the contacts 79 and 80, while the circuit to the street is broken at the contacts 81 and 82. Under these circumstances the apparatus is in condition to send in another alarm in the case of fire.

The alarm mechanism of the present invention is of the normally closed-circuit type, but for some reason or other it may occur that after the sending of the alarm the drum 11 stops at a point where the circuit through the conductors 66, 67 is open. Under such circumstances it might transpire that a considerable number of the street alarm boxes would be rendered inoperative because of a circuit being open instead of closed. To overcome this difficulty is the purpose of the switch arm 71 since as soon as the sending apparatus reaches the conclusion of its operative movement the street circuit is reestablished in the closed circuit condition by the bridging of the terminals 81 and 82, while the local sending apparatus, after the operative movements, is cut out of service, and can only be restored manually.

While the device has been described as including both the telegraphic and telephonic transmitters it will be understood that the device may be provided with either transmitter to the exclusion of the other if such an arrangement be desirable.

What is claimed is:

1. An automatic fire alarm system, comprising means for producing and transmitting signals to a distance, means for actuating the signal producing means and having a constant tendency to operate, electrically controlled means for holding the actuating means against operation and responsive to fire conditions to cause the release of said actuating means, telephonographic means for reproducing a phonograph record and transmitting the reproduced sounds to a distance, and connections between the actuating means and the telephonographic means for causing the actuation of the latter with the signal producing means.

2. An electric fire alarm system comprising automatic means responsive to fire conditions for sending a signal to a distant

point, and manually-operable means for causing the operation of the signal sending means independently of the portion of the latter directly responsive to fire conditions, said manually-operable means being provided with shatterable means holding it in the inactive position and located with respect to the manually operable means to be shattered by a force moving said manually operable means to the closed position.

3. An electric fire alarm system, comprising means for automatically sending a signal to a distant point, means automatically responsive to fire conditions for causing the operation of the signal sending means, manually-operable means for causing the operation of the signal sending means independently of the means automatically responsive to fire conditions, shatterable means for holding the manually operable means in the inactive position and in the path of the said manually operable means to be broken by a force moving said manually operable means to the active position, and telephonographic means associated with the signal sending means and operable simultaneously therewith in response to either fire conditions or the manually operable means.

4. An automatic electric fire alarm system comprising electric means for the transmission of signals to a distance and provided with controlling means responsive to fire conditions, and normally-open circuit-closing means responsive to the first-named means at the completion of its operation for electrically short-circuiting said first-named means.

5. An electric fire alarm system comprising electrically controlled means for the production of signals at a distance, means responsive to fire conditions for controlling the first-named means, telephonographic means associated with the first-named means for transmitting information by the operation of the first-named means, manually-operable means for causing the actuation of the electrically controlled means and the telephonographic means independent of the means responsive to fire conditions, and means controlled by the first-named means for short-circuiting the signal sending means at the completion of the signal sending operation.

6. In an electric fire alarm system, means for the production and transmission of electrical impulses in predetermined order and at predetermined speed over an alarm circuit for causing intelligible signals at a distance, and means for producing as a part of the same orderly set of intelligible signals and immediately preceding them a succession of impulses so rapid as to serve as a preliminary warning signal distinct from the alarm signal.

7. In an apparatus for the sending of fire

alarm signals, circuit making and breaking devices in prearranged order and movable at a predetermined speed with the circuit making and breaking device first active including a multiple circuit making and breaking means active at a materially higher rate of speed for the sole production of a warning signal immediately preceding and characteristically distinct from the sending of the intelligible signal impulses.

8. In an electric fire alarm signal apparatus, circuit making and breaking devices, and a rotatable member carrying pins for engaging the circuit making and breaking devices in predetermined order and at a predetermined speed, the pin first active in the operation of the apparatus being prolonged in the direction of movement and provided with a toothed or serrated surface for imparting to the circuit making and breaking device a rapid succession of actuations, whereby the production of the distant signal is preceded by a warning signal of different characteristics.

9. In an apparatus for electrical transmission of fire alarm signals, circuit making and breaking devices arranged to cause electrical impulses in predetermined order to produce the signal, a spring driven train of gearing for actuating the circuit making and breaking devices in the predetermined order, a governor for determining the speed of the train of gearing, a brake for the governor, electromagnetic means for actuating the brake in a direction to cause the release of the governor and the train of gearing controlled thereby, and circuit controlling means in circuit with the electro-magnetic means and under the control of the spring driven gearing for breaking the circuit of the electro-magnetic means to cause the brake to stop the train of gearing.

10. In an electric apparatus for the transmission of fire alarm signals, mechanically operated driving means, circuit making and breaking means connected to the mechanically operated means for actuation thereby and provided with connections for the electrical transmission of the signals to a distance, a phonographic apparatus connected to the mechanically operated driving means for actuation thereby with the phonographic apparatus and the circuit making and breaking means simultaneously active, and telephonic apparatus in operative relation to the phonographic apparatus for transmission to a distance of sounds produced by said phonographic apparatus.

11. In an electric apparatus for the transmission of fire alarm signals, mechanically operated driving means, electric circuit controlling means connected to the mechanically operated driving means for actuation thereby, a phonographic apparatus connect-

- ed to the mechanically operated driving means for actuation thereby, a brake for the phonographic apparatus, electro-magnetic means for controlling the brake, and 5 telephonic apparatus in operative relation to the phonographic means for the transmission of sounds produced by the phonographic apparatus, the telephonic apparatus being provided with electromagnetic 10 means for including it in the telephonic circuit on the energization of the electromagnetic means, and said last-named electromagnetic means and the electromagnetic means controlling the brake having common 15 means for controlling the circuit thereto.
12. In a fire alarm apparatus for the production of electrical impulses for the operation of distant signals, means for the production of electric impulses for causing distant signals, means for actuating the first-named means, electromechanical means for controlling the actuating means and including a switch, a normally open circuit having circuit terminals adapted to be bridged by 20 the switch for the short-circuiting of the electromechanical means, and means driven by the actuating means and timed in movement to cause the bridging of the circuit terminals by the switch on the completion of 25 the sending of the signal impulses.
13. In an apparatus for sending fire alarm signals, circuit making and breaking devices for producing electrical impulses, driving mechanism for the circuit making and breaking 30 devices, electromagnetic controlling devices for the driving mechanism, circuit terminals for the electromagnetic controlling means, a switch for closing said circuit terminals, other circuit terminals in the path 35 of the switch for short-circuiting the means for producing the electrical impulses when said circuit terminals are bridged by the switch, and means actuated by the driving mechanism and movable in timed relation 40 to the circuit making and breaking devices for causing the switch to be moved from closing relation to the terminals of the electromagnetic means to closing relation to the short-circuiting terminals.
- 50 14. In a fire alarm apparatus, means for the production of electric impulses for causing distant signals, driving means for the first-named means, electromagnetic means for controlling the driving means, a switch 55 lever and circuit terminals normally bridged thereby and included in circuit with the electromagnetic means, said lever having a normal tendency away from said circuit terminals, other circuit terminals in the path 60 of the lever and adapted to be bridged thereby for short-circuiting the electrical impulse causing means, a latch for holding the lever

in bridging relation to the first-named terminal, and a traveler actuated by the driving means and movable into engagement 65 with the latch at the completion of the active movement of the means for producing electrical impulses to cause the release of the lever to movement out of engagement with the first-named terminals and into engagement 70 with the second-named terminals.

15. In a fire alarm apparatus, means for causing electrical impulses for the production of distant signals, driving means for the first-named means, a shaft connected to the 75 driving means for actuation thereby, said shaft having different sets of screw threads thereon, phonographic apparatus connected to the driving means and in part controlled by one of the screw threaded portions of the 80 shaft, telephonic apparatus in operative relation to the phonographic means, electromagnetic controlling means for the driving means having circuit terminals included therein, a switch lever having a normal tendency in one direction, other circuit terminals in the path of the switch lever in the direction of its normal tendency, a latch for the switch lever, and a traveler controlled by the other screw threaded portion of the 85 shaft and movable into engagement with the latch to release the lever at the completion of the active movement of the circuit controlling means.

16. In a fire alarm apparatus, means for 95 the production of electrical impulses to cause the actuation of distant signals, a driving means therefor, electromechanical controlling means for the driving means for stopping and releasing said driving means, a 100 switch for controlling the electromechanical means and having a normal tendency to open the circuit of the electromechanical means, and means for causing the switch to move to the open circuit position with respect to the 105 electromechanical means under its normal tendency, comprising a latch for holding the switch in the circuit closing position, a traveler provided with a member having a mutilated nut and having one end accessible 110 for manipulation, and a threaded shaft adapted to be engaged by the nut and connected to the driving mechanism for movement thereby to engage the latch and release the switch.

115 In testimony, that we claim the foregoing as our own, we have hereto affixed our signatures in the presence of two witnesses.

GEORGE B. RATTERMANN.
